United States Patent Office

Des. 194,711
Patented Feb. 26, 1963

194,711
BOTTLE

Robert F. Bateman, Brighton, Mass., assignor to The Carter's Ink Company, Cambridge, Mass., a corporation of Massachusetts

Filed June 14, 1962, Ser. No. 70,542

Term of patent 14 years

(Cl. D58—6)

FIG. 1

FIG. 2

FIG. 3

FIG. 4

FIG. 5

FIG. 1 is a view in perspective of a bottle, showing my new design;

FIG. 2 is a view in front elevation thereof;

FIG. 3 is an end elevational view taken from the right of FIG. 2;

FIG. 4 is an end elevational view taken from the left of FIG. 2; and

FIG. 5 is a bottom plan view thereof.

I claim:

The ornamental design for a bottle, substantially as shown.
